UNITED STATES PATENT OFFICE

2,505,062

LABELING MACHINE

George Olm, Astoria, N. Y., assignor to Edward Ermold Company, New York, N. Y., a corporation of New York

Application April 19, 1946, Serial No. 663,348

7 Claims. (Cl. 216—38)

1

This invention relates to labelling machines, and has for its object to provide means for securing neck labels to the bottle necks.

As neck labels extend more than 180° around the circumference of the neck of the bottle, the known wipers like those used for applying the main labels to the body of the bottle fail in securing the ends of the neck labels to the bottles beyond the frontal 180° of the bottle neck. The problem of efficiently securing the ends of the label to the rear 180° surface of the bottle neck by automatic mechanical means became important.

The invention consists in the provision of wipers of yieldable and resilient rubber or the like with a concave contour at each of their inner surfaces, with the portion of the wipers of lesser thickness secured to supports and with the portion of the wipers of greater thickness extending free of the support, the wipers with the gradually decreasing space between them acting as a pressure means upon the portion of the neck label which extends over the lateral sides of the bottle (in contrast to the front and rear sides), and the thickest ends of the wipers acting over the label ends at the rear of the bottle, when the ends of the wipers of less thickness have been brought near each other. With the passage of the bottle between the wipers, the wipers act as pressure members along the rear 180° of the neck circumference to press the ends of the neck label against the rear portion of the bottle neck, the inward inherent resiliency of the outwardly pressed thickened ends of the wipers serving to exert a pressure action against the rear ends of the neck label.

The invention consists further in the means for actuating the wipers from their open position to their closing position, which comprise vertical rods to which the horizontally disposed wipers are secured, and means for laterally moving a pair of such vertical rods in respect to the vertical axis of the bottle, either in continuous movement or in continuous movement with time-interludes, as may be desired. Such vertical rods are alternately secured to horizontally movable bars, and these are actuated in opposite directions, by a pinion meshing with racks on such bars, one of said bars being actuated by a lever in turn actuated by the aid of intermediary means controlled by a cam of a contour determining either the continued or intermittent movement of the vertical rods, and hence the wipers which are arranged in a horizontal plane, and which have vertical contours through which the neck of the bottle to be labelled passes.

The invention will be further described hereinafter, embodiments thereof shown in the drawings, and the invention will be finally pointed out in the claims.

2

In the accompanying drawings,

Figs. 1 to 4 are diagrammatic views showing the various positions of the improved wiper in relation to a bottle neck;

5 Fig. 5 is a rear view of a part of the labelling machine showing the application of the improvement thereto;

Fig. 6 is a sectional side view taken on line 6—6 of Fig. 5 omitting the cam, follower and 10 gearing of Fig. 5;

Fig. 7 is a top view taken on line 7—7 of Fig. 6;

Fig. 8 is a front view of Fig. 7;

Fig. 9 is a vertical transverse section taken on 15 line 9—9 of Fig. 8;

Fig. 10 is a bottom view of part of Fig. 8;

Fig. 11 is a top view of one of the wipers; and Fig. 12 is a face view of the wiper shown in 20 Fig. 11.

Similar characters of reference indicate corresponding parts throughout the various views.

Referring to the drawings and more particularly to Figs. 1 to 4, the bottle is moved in the direction of the arrow 1 by the known bottle 25 pushers (not shown) of a known labelling machine to a position between the spread out wipers 10 as shown in Fig. 1. Means for applying a glued label 8 to the front of a bottle are part of a standard labelling machine and are not shown in the drawings.

The improved wipers 10 are made of rubber or the like, and have a rigidity to maintain them in their initial shape until force is applied. They have an inherent resiliency to return them to 35 their initial contour after any deformation has resulted from applied pressure. The inner faces 10a of the wipers 10 are curved and the ends 11b are angular shaped to provide a backing for the tips 11c. The outer faces are straight. In

40 consequence, one end is of greater thickness than the other end. The thinner ends have bores through which screw bolts 14 pass and these screw bolts 14 have their heads in countersunk portions of the wipers. Such screw bolt 14 has 45 threads, which engage a threaded bore 11a of a metal support 11 which has a bore 15a, for the entrance of a vertical rod 15, secured by screw bolts 12 to the metal support 11. Preferably each wiper has a flange 10a seated in a recess 50 10b of the support 11.

A pair of wipers 10 to provide a secure hold in addition to the screw bolt 14 with each concave curved part 10a facing each other, and a wiper at each lateral side of a bottle neck are arranged 55 to apply a label. The vertical rods 15 are moved towards and from each other, preferably intermittently timed with the progress of movement of the bottle through a pair of wipers 10.

The first position of the wipers is shown in 60 Fig. 1, the bottle neck 9 having just received its

label 8 due to the movement of the bottle on its track against a label bearing an adhesive, which label has just been released from a label support, as known in the labelling machine art.

As the bottle continues to be moved on its track, the wipers are moved towards each other by the vertical rods 15, and thereby the label is secured along that portion of the bottle neck corresponding to about its front 170° (Fig. 2).

The bottle continuing to move, the wipers move further towards each other, and are deformed, but due to this deformation, the wipers not alone press the label against the lateral sides of the neck, at the transverse diameter of the bottle neck at right angles to the direction of movement of the bottle, but press beyond the 180° part of the neck, and thereby press the ends of the label against the rear part of the bottle neck (Fig. 3). As the bottle continues in its movement, the ends 11c of the wipers move along the ends of the label giving a pressure to the same, and, so to say, snap along the ends of the label, while the bottle moves beyond the wipers (Fig. 4). The label 8 may be longer than as shown, and still has its ends pressed by the wipers.

The wipers 19 are then moved away from each other to their extreme open position as shown in Fig. 1, ready for the next bottle and its neck label application.

The closing movement of the wipers is substantially continuous, but preferably these wipers have momentary rest periods, to more securely cause the adhesive to adhere, and such continuous closing with such preferred intermittent or momentary rest periods, may be readily accomplished by the shape of the cam on the cam gear, and the cam may be shaped by any mechanic when instructed so to do, and therefore the outline of the cam is not shown in the drawings.

With the foregoing operation in mind, the operative mechanism will now be described.

Referring now to Figs. 5 to 10, the bottles 9 are moved by well known means forming a part of a known labelling machine, along the tracks 30, suitably supported by the frame 31 of the labelling machine. The upper part of the frame 31 suitably supports a bell crank lever 32, by the intermediary of a bracket 33. The end of this lever 32 engages a vertical pin 35 fixed to a movable bar 41a (Fig. 10). A pinion 36 is rotatable mounted on a pin 37 supported by the bar 38. The stationary bar 38 is secured at 38a to the frame 31 of the machine. A vertical standard 42 is secured at its top 44 to the bar 38. The lower part of the standard 42 supports the known wipers 60 by bolts 43, which wipers 60 are shown in dotted lines since they are not part of the invention and which wipers are flat pieces of rubber or the like, and which wipers are used to apply the main or body labels which require less than 180° of adhesive surface. The bar 41a has a slot 45 (Fig. 10). The rack 40 is part of the bar 40a, and the rack 41 is part of the bar 41a held by screws 41b. One of a pair of wiper supporting rods 15 is secured to the movable bar 41a, and the other of that pair of wipers is secured to the movable bar 40a. Normally the rods 15 are spaced from each other as shown in Fig. 8, namely, with the widest space possible between them. Each alternate rod 15 is secured to the bar 40a controlled by rack 40, and each of the intervening rods 15 is secured to the bar 41a controlled by the rack 41. So with each movement of the bars 40a and 40b a pair of vertical rods 15 are moved to and fro. The number of pairs of ver-

tical rods 15 depends on the number of tracks, and the number of tracks depends on the width of the labelling machine. The lever 32 engaging the pin 35 moves the bar 41a and its rack 41, and the rack 41 rotates the pinion 36, and the pinion 36 moves the rack 40 and bar 40a. Thereby, the aforesaid open position of any pair of rods 15 is changed to a closed position, and when the pressure of the wipers 19 has been completed, the rods are moved in the opposite direction until the open position is again obtained. The rods 15 have brackets 16 secured by bolts 17 to the bars 40a and 41a respectively.

As stated, the rack 41 is secured by screws 41b to the extension bar 41a, and the rack 40 is secured by screws 40b to the extension bar 40a.

The bell crank or elbow lever 32 is operated by any suitable mechanism under cam control. In Figs. 5 and 6, a lever 50 secured to the elbow lever 32 is pivoted at 52a, to a supporting bracket 33 on the frame of the machine. The end of the lever 50 is pivotally connected at 51 to a crank arm 52 secured to a shaft 53. The shaft 53 is rotatably moved by lever 54 (Fig. 5) having a cam follower 55, engaging a cam 56, of suitable conformation to cause the pin 35 to which one end of the bell crank is pivoted, to be moved, to and fro, the pin 35 being made part of the rack bar 41a (Fig. 10).

The cam 56 is rotated on a shaft 58, which has a gear 59, suitably actuated, in the manner known.

As stated, known wipers 60 of the main label, which label does not present the same problem as a neck label, are shown in Fig. 5 in dotted lines. Should it be desired to have main labels applied to move more than 180° of the bottle circumference, then the main label wipers would be modified according to the invention described and embodied in the improved neck label wipers.

Any suitable number of pairs of wipers may be arranged across the front of the labelling machine, depending on the number of bottles fed in, that is, upon the number of tracks 30; but for simplicity such a plurality has not been shown.

I have described several forms of my invention, but obviously various changes may be made in the details disclosed without departing from the spirit of the invention as set out in the following claims.

I claim:

1. In a labelling machine having a track for the support of moving bottles to be labelled, a pair of wipers, one disposed at each side of the bottle during the passage of the bottle between the wipers, and adapted to retain a label to be applied to the bottle neck, the combination of a support for each wiper, a yieldable and resilient rubber wiper having a concave contour at its inner surface with a portion of lesser thickness at the support and secured to the support, and a portion of greater thickness extending free of the support, and means at the upper end of each support for moving the wipers towards each other during the passage of the bottle between the wipers, and for moving the wipers away from each other after the bottle has passed beyond the wipers.

2. In a labelling machine, a wiper of resilient material, having a plane top and bottom and a plane side, the side opposite to the plane side being concavely curved, with one end of the wiper being narrower than the other end, said narrower end having a bore for a fastening member.

3. In a labelling machine, a pair of wipers

spaced to permit the passage between the same of a neck of a bottle, said wipers extending in the direction of movement of said bottle and having curved opposed inner surfaces converging toward each other, and means for moving said wipers towards each other, including a vertical support for each wiper, a rack bar secured to each support, a pinion between said rack bars for moving the rack bars in opposite directions, and means for moving the pinion to and fro, the movement of the pinion in one direction moving each rack bar in one direction, and the movement of the pinion in the opposite direction moving each rack bar in the direction opposite to its first movement, whereby the wipers are moved towards and away from each other.

4. In a machine for applying labels to receptacles moving along a track, a pair of resilient wipers, separate movable means engaging each wiper and supporting the wipers above and adjacent to opposite sides of said track, said wipers having free ends extending substantially in the direction of movement of said bottles, and having inner surfaces converging toward each other in the direction of movement of said receptacles, and means for moving said movable means toward and away from each other.

5. In a machine for applying labels to receptacles, a support, a pair of supporting elements mounted on said support for movement toward and away from each other, means for moving a receptacle between said supporting elements, a pair of resilient wipers, each connected to a different one of said elements and having a free end portion extending in the direction of movement of said receptacle, said wipers having inner surfaces converging toward each other in the direction of movement of said receptacle for en-

gagement with opposite sides of said receptacle, and means for moving said supporting elements toward and away from each other.

5 6. In a machine for applying labels to receptacles, a support, a pair of supporting elements mounted on said support for movement toward and away from each other, means for moving a receptacle between said supporting elements, a pair of resilient wipers, each connected to a different one of said elements and having a free end portion extending in the direction of movement of said receptacle, said wipers having concavely curved inner surfaces converging toward each other in the direction of movement of said 10 receptacle for engagement with opposite sides of said receptacle, and means for moving said supporting elements toward and away from each other.

10 7. In a labelling machine, a pair of resilient 20 wipers for engaging opposite sides of a receptacle moving along a path, and means engaging one end of each wiper for supporting the wipers in substantially parallel relation to said path, said wipers having inner opposed concavely 25 curved edges converging in the direction of movement of said receptacle from adjacent their said one ends toward their opposite ends.

GEORGE OLM.
